METHOD OF MAKING TAPPETS

Harold I. Dyer, Battle Creek, Mich., assignor to
Wilcox-Rich Corporation, a corporation of
Michigan

Application July 5, 1934, Serial No. 733,821

5 Claims. (Cl. 29—156.7)

My invention relates to the construction of steel valve tappets for internal combustion engines. These devices are used to transmit the thrust of the cam to valve stem. They require a hard wear resisting face for contact with the cam and also a face which is not brittle or easily fractured.

Heretofore it has been customary to construct tappets with a steel body member and a cast iron head or wearing face for contact with the cam.

10 Hard cast iron provides as good a wearing surface as is known, but it has the disadvantage of being more fragile and brittle than steel. Increased engine speeds and valve loads have made it necessary and desirable to provide a tappet construction in which the head member has practically comparable wearing qualities to cast iron, but is stronger and less subject to fracture by impact.

Various steel constructions have heretofore 20 been proposed, among them the constructions wherein a piece of relatively hard wear-resisting steel is attached to a rod or body of softer steel of the same size and the combined article is then forged to shape and join the head and body members as desired. This requires a considerable amount of forging and a deformation and reworking of the hard steel facing material and the body member. Steel suitable for the facing member is not easily machined, or worked by forging, 30 and it is consequently desirable to provide a construction in which the forging and machining of the face member may be substantially eliminated.

One object of my invention is to provide a tappet construction wherein a hard steel facing member may be attached to a softer steel body and secured thereto without the necessity of reworking the hard steel head or facing member to any substantial degree.

Another object is to provide a tappet construction wherein the forging operation is performed 40 only upon the soft steel body portion of the tappet and wherein the amount of forging necessary to form the tappet is substantially diminished.

With these and other objects in view, my invention consists in the combination, arrangement and construction of the various parts of my improved structure described and claimed in the accompanying specification, and shown in the drawings, in which:

50 Figure 1 is a longitudinal cross-sectional view of a blank for a tappet body constructed according to my invention.

Fig. 2 is a longitudinal cross-sectional view of a 55 tappet body after being formed by forging, and

of a steel head or face member which is to be attached thereto.

Fig. 3 is a view in elevation and partly in section of the body and head member joined together, showing one form of the ultimate construction. 5

Fig. 4 is a longitudinal cross-sectional view showing a modified form of tappet embodying my invention.

Fig. 5 is a third modification of tappet embodying my invention shown in longitudinal cross-section. 10

Fig. 6 is a fourth modification of tappet construction embodying my invention and shown in longitudinal cross-section. 15

In Fig. 1 I have shown a preformed tappet body or stem 1 made of a machinable steel which is capable of suitable hardening by heat treatment. This may be fashioned as a screw machine product, or by any other suitable means, to provide a hollow tubular body portion with a relatively large bore 2 through the major part thereof to provide relatively thin walls and eliminate as much weight as possible, and with a reduced bore 3 and consequently thicker walls which may be internally threaded to receive the threaded shank of the conventional adjusting screw, not shown, which is customarily inserted in the ends of these tappets to adjust the clearance between the end of the valve stem and the tappet, as is well understood by those familiar with the art. The end opposite to the reduced bore is formed with thickened walls 4, as shown, which is later fashioned, as hereinafter explained, to provide a support for the head or wearing face of the tappet. 20 25 30 35

In Fig. 2 I have shown the body 1 after a forging operation in which the thickened end 4 has been forged to form an outwardly extending annular and lateral flange 5. The portion of the thickened part of the wall 4 which is not contained in the lateral flange 5 has been forced inwardly, as shown, and forms a thickened wall portion at the flange end of the tappet body which restricts the enlarged bore therein and which provides a reinforced neck portion for 40 the tappet immediately beneath the flange 5 to which the head or cam contacting face of the tappet is to be secured. The cam contacting face or head of the tappet is composed of an annular disc 6 of a hardenable impact and wear-resisting metal or alloy which may be punched from sheet stock or cast to substantially the desired ultimate size. The metal is preferably of somewhat different character than that of the tubular body of the tappet. Steels suit- 45 50 55

able for this purpose, such as those comparable to the standard S. A. E. steel specification 52-100, are not easily or readily machinable and forgeable and are preferably handled without a great deal of forging or machining. They may be heat treated to a high degree of hardness and wear resistance. The metal of the tubular body 1 may be comparable to the standard S. A. E. steel specification 1035 which is readily machinable and forgeable, and which may also be hardened to such degree as is necessary to provide a suitable wearing surface on the tappet body. The greatest wear naturally comes upon the face or head of the tappet which is in contact with the cam, the wear on the body occurring only in its contact with the sleeve guide, and the surfaces of the tappet body and the guide are not subjected to the impact or pressure or friction which the cam contacting face must bear, and therefore do not require as great hardness or wear-resisting quality as the face member.

After the body has been flanged and formed, as shown in Fig. 2, the head member 6 is superposed over the flange and is welded to the flange by seam welding at 7 between the outer edge of the flange 5 and the overhanging edge of the head member 6. This adequately secures the head member to the body and provides a construction in which substantially all of the machining and forging is accomplished upon the material of the body which is more readily subject to these operations, and the head need only be ground slightly to bring it to final dimensions and finish, as it has been cast, or punched from the stock sheet, to substantially the ultimately desired size.

A modified form shown in Fig. 4 is constructed in the same manner as the form shown in Figs. 1, 2 and 3, previously described, the only difference being in the formation of the flanged end of the body by the forging operation which is slightly different from the formation shown in Fig. 2, and provides a tapering flange 5 to which the head member 6 is attached by seam welding as described in connection with Fig. 3.

In the modification shown in Fig. 5 the flanged end of the body member 1 is not provided as shown with the thickened wall portion beneath the flange, although this may be incorporated in this form if desired. In this modification, the flange 5 is tapered and provided with a chamfered outer edge 10. The head member 6 is also provided with a chamfered inner edge 11 and the head member 6 is then superposed upon the flange 5 as shown with the inner edges of the chamfer on each part contiguous and providing a notch or a groove 12 around the edge of the joined parts. The parts are then secured together by puddle welding which consists in puddling a welding material in this groove 12 to form an integral bond between the members.

In the modification shown in Fig. 6 the flanged end of the body is formed in much the same manner as that shown in Fig. 5 except that the flange 5 is not tapered to the extent shown in Fig. 5 but is somewhat thicker and is terminated short of the outer edge of the head member 6. In this form, as in Fig. 5, the walls of the body member beneath the flange may be thickened if desired, as shown in Figs. 3 and 4. In this form the head member 6 is formed to a cup-shape as shown with an upturned flange around the edge of the member which fits over the outer edge of the annular flange 5. The head member is then joined to the body member 1 by means of

a seam weld along the joint line of the contiguous parts as at 13.

The construction described enables the tappet to be formed of steel materials having different characteristics, each suitable to the functions to be performed and each also suitable and adapted to the various machining and forging operations which must be performed upon it. The body member which must be of a material that may be readily machined and forged is formed of a metal or alloy having characteristics readily permitting these operations. The head member which must be of a material having high wearing qualities, not easily machined or forged, may be provided and secured to the body member with a minimum of machining or forging operations. This construction and method provides a sound and strong tappet of different materials particularly adapted to the service required of them, and it also provides a cheap, and efficient method of making such a tappet.

Formal changes may be made in the specific embodiment of the invention described without departing from the spirit and substance of the broad invention, the scope of which is commensurate with the appended claims.

I claim:

1. The method of making a tappet comprising: providing a tubular body of machinable and forgeable steel with a relatively small bore in one end thereof and a relatively large bore in the other end thereof; forming an annular lateral flange on said relatively large bore end; and then securing a preformed disc of wear resisting, but relatively non-machinable and non-forgeable steel upon the flange of said steel body by seam welding the edges of said flange to the underside of said disc.

2. The method of making a tappet comprising: providing a tubular body of machinable and forgeable steel with a relatively small bore in one end thereof and a relatively large bore in the other end thereof; upsetting the relatively large bore end to thicken the walls thereof and to form an annular lateral outwardly extending flange thereon; and then securing a preformed disc of wear resisting, but relatively non-machinable and non-forgeable steel to said flange on said steel body by seam welding the edges of said flange to the underside of said disc.

3. The method of making a tappet comprising: providing a tubular body of machinable and forgeable steel with a relatively small bore in one end thereof and a relatively large bore in the other end thereof; forming an annular outwardly extending lateral flange on the large bore end of said body and chamfering the outer edges of said flange; superposing a preformed disc of wear resisting, but relatively non-machinable and non-forgeable steel and having a chamfered inner edge upon said annular flange; and then securing said disc to said flange by welding in the groove formed by the chamfered edges of said disc and flange.

4. The method of making a tappet comprising: providing a tubular body of machinable and forgeable steel with a relatively small bore in one end thereof and a relatively large bore in the other end thereof; forming an annular outwardly extending flange on the relatively large bore end of said body; superposing a preformed disc of wear resisting, but relatively non-machinable and non-forgeable steel and having an upturned flange around its edge, upon the

annular flange of said steel body with the flange of said disc embracing the edge of the annular flange on said body; and then welding said parts together at the underside of the disc along the line of contiguity of said respective flanges on said body and disc.

5. The method of making a tappet comprising: providing a tubular body of machinable and forgeable steel with a relatively small bore 10 in the one end thereof and a relatively large

bore in the other end thereof; forming an annular outwardly extending lateral flange on the large bore end of said body; superposing a pre-formed disc of wear resisting, but relatively non-machinable and non-forgeable steel upon said annular flange of said steel body; and then securing said disc to said flange by welding the same thereto without upsetting or deforming either said flange or disc. 5

HAROLD I. DYER. 10
